UNITED STATES PATENT OFFICE

2,387,877

SHARPENING DEVICE

Fred E. Broberg, Racine, Wis.

Application October 30, 1944, Serial No. 561,051

2 Claims. (Cl. 51—116)

My invention refers to sharpening devices of the rotary type such as disclosed in my prior patents, Numbers 2,019,471 and 2,264,065 issued respectively to me October 29, 1935, and November 25, 1941.

The primary object of my present invention is to provide angularly disposed abrasive shoes, such as disclosed in my previous patents, with means for adjusting the angular position of said shoes, with reference to the point of grinding, whereby the bevel of a knife blade at the cutting edge can be varied.

Another object of my invention is to provide obliquely disposed shafts for the abrasive shoes connected at their inner ends by a common pivot or center, about which the shafts and abrasive shoes are adjusted as to angle, whereby practically no change of height, at the grinding point or front end, is developed. In other words, the shafts are mounted on a common axis, whereby the height of the shoes, at their front or grinding point, are not varied.

A further object is to provide a two part guide for a knife blade which is to be ground, whereby said blade, under certain conditions, can be sharpened directly up to the hilt of the handle, and to provide a manually controlled lever mechanism associated with the outer ends of the obliquely disposed shafts, whereby they may be selectively raised or lowered to change the angle of same and be locked in such changed positions.

Another object of my invention is to provide a fixed anchor point carried by the casing upon which the grinder shafts are pivoted, and to provide pairs of grinding shoes composed of abrasive material with yielding means at the ends of carrying arms, whereby the grinding elements or shoes, when engaging the surface of a cutting blade, may be slightly cushioned as to pressure.

A still further object of my invention is to provide a simple and economical means for anchoring the cushioned grinding shoes whereby they may be readily removed for dressing or renewal purposes.

With the above and other minor objects in view, the invention consists in certain peculiarities of construction and combination of parts as will hereinafter be fully set forth with reference to the accompanying drawing.

In the drawing:

Figure 1 represents a side elevation of a rotary sharpener or grinder embodying the features of my invention, the same being partly broken away and partly in section to more clearly illustrate structural features.

Figure 2 is an enlarged cross sectional view of same, the section being indicated by line 2—2 of Figure 1.

Figure 3 is a fragmentary magnified plan view, the same being partly in section as indicated by line 3—3 of Figure 1 and illustrating the fixed pivot of companion pivotal connected grinder shafts.

Figure 4 is a detailed sectional view showing 10 pivoted means for varying the angle of the grinder shafts, as indicated by line 4—4 of Figure 1.

Figure 5 is a fragmentary faced view of the feed end of the machine illustrating the blade 15 guide with the guide handle in section, as indicated generally by line 5—5 of Figure 1.

Figure 6 is a fragmentary detailed view of the casing side wall, illustrating the casing guide slot means for permitting adjustment of one of the 20 grinder shafts.

Figure 7 is a detailed plan view illustrating one 25 of the abrasive shoes and associated arm which is yielding, connected at ends of the shoe, parts being broken away and in section.

Referring by characters to the drawing A indicates a casing provided with a removable cover cap B, which cap is partly circular in form and provided with a central slot C formed by parallel connected walls, the bottom D, of which serves as 30 a guard for the blade of a knife to be sharpened, as indicated in dotted lines E.

The casing has secured thereto a bracket 1, as best shown in Figures 1 and 3 of the drawing, and the end bracket terminates in a stud 2, upon 35 which is pivoted the inner end of a pair of grinder shafts 3, which shafts, as shown, are at angles relative to each other or obliquely disposed, and the outer ends of said shafts are guided in vertical disposed slots 4 of the casing, whereby said 40 shafts are adjusted to vary the relative angle thereof.

As best shown in Figures 1 and 2 of the drawing, the free ends of the shafts are supported by straps 5, the lower ends of which are pivotally connected to arms of a yoke or bell crank lever 6, which lever in turn is pivoted to the walls of the casing by studs 6'.

The yoke is formed with a hollow centrally positioned arm 7 having mounted therein a spring 50 controlled plunger stem 8, which stem extends through a vertically positioned slot 9, of the casing. The slot walls are formed in a series of companion circular pockets 9', which pockets are adapted to selectively engage the conical hub 10 55 of a button 10'.

By this link connection between the button and grinder shafts, the shafts may be selectively raised or lowered to vary the angle thereof and to lock the parts in their adjusted position, due to the engagement of the conical hub 10 and the wall pockets 9' of the slot, which action is under manual control.

Rotatably mounted upon each of the shafts 3, are spider hubs 11, carrying oppositely disposed radial spokes 12, it being understood that the spokes of one spider in assemblage are positioned at a right angle to the spokes of the opposite spider.

As best shown in Figures 1 and 7 of the drawing, the spokes 12 terminate with arms 13 having end apertures 13' for the reception of headed studs 14, which are secured to segment shaped abrasive shoes 15, the ends of which, as is best illustrated in Figure 7 of the drawing, are slightly flared. The abrasive shoes are removably anchored to the spoke arms by the studs 14 and between the face of the arms and abrasive shoe is a rubber washer 16 which serves as a cushion and permits slight yield of the shoes at both ends. The shoes are fastened to the arms 13 by a leaf spring 17, having a key hole slot 18 in each end thereof. The slots receive the studs 14 and the outer face of the spring engaging the shouldered heads of the studs 14 when the spring is slid in one direction to lock the shoes in position. To release the studs 14, the spring is shifted longitudinally in the opposite direction until the studs register with the enlarged ends of the slots, at which time the spring 17 can be lifted off the studs. The arms 13 at the leading ends thereof are provided with recesses into which are adapted to snap the resilient inturned forward ends 17' of the springs 17. This creates a less tension on the springs at the leading ends thereof. Consequently, the rear ends of the shoes are held in place by a greater tension than at the front, which gives the pads the desired wiping action on knife being sharpened at the rear ends of said shoes.

As shown in my previous patent, the rotary spiders are driven by belts F from a suitable motor, indicated in dotted lines, it being noted in this instance that the hubs 11, which form the driving pulleys for the abrasive elements, are circular in form without grooves for the belt, whereby sufficient play of the belt is permitted to accommodate variation in the angular adjustment of said hubs.

The front ends of the hubs carry toothed wheels 18, with their lower portions intermeshed upon a vertical line intersecting the center anchorage point of said shafts, hence, while these teeth gears serve to synchronize the independently driven abrasive feature elements, adjustment relative to the angle of the shafts will not interfere with

the proper tooth mesh or tend to bind with reference to the teeth of the wheels.

As indicated in dotted lines by character E, the sharpener has inserted therein a knife and when this blade is slowly moved back and forth, it will be effectively ground as the wiping abrasive shoes contact with the cutting edge of the blade at the point indicated by the black dot x. In the movement back and forth of the blade, it is guided in the throat of a V-shaped slot 19, formed in the end of a spring plate 20, which is secured to the front wall of the casing. The blade is also guided by a grooved roll 21 of a guide block 22, which guide block is pivoted at its lower end 23 in the walls of a casing slot and the end 23 is formed with a rectangular head 23' which engages the lower portion of the plate spring 20. Said plate spring in addition to serving as a guide under certain conditions also serves as a spring element to lock the guide block in its upper functional position as shown in Figure 1 or in its shifted position as indicated in dotted lines in said figure.

The purpose of this shiftable guide block, carrying the wheel 23, is to accommodate the offset hilts of knife handles which may have shields thereon, which are known to the trade as the "French type," and in sharpening this type of knife, it is desirable to grind the blade as close to the intersection point of the hilt and blade as possible, hence in the last mentioned type of knife the guide block 22 is swung downwardly, in order that the hilt may have more clearance and can thus be moved inwardly until it contacts with the casing walls or thin spring plate 20.

I claim:

1. A blade sharpener, comprising a companion pair of spaced angularly disposed fixed shafts having their inner axis lines intersecting, rotary spiders mounted upon the shafts, abrasive shoes carried by the spiders, a fixed pin in pivotal union with the inner ends of the shafts and intermeshed gear wheels carried by the spiders, independent driving means connecting the aforesaid spiders, and means for manually adjusting the outer ends of the shafts, whereby the angularity of same is varied.

2. A blade sharpener comprising a casing, a companion pair of obliquely disposed rotary abrasive shoes adapted to grind a blade at their converging point, shafts for the rotary abrasive shoes having their inner ends in pivotal union with each other, a pivoted yoke mounted in the casing in link connection with the outer ends of said shafts, a manually controlled means connected to the yoke and extending through the casing for adjusting the angular position of the shafts.

FRED E. BROBERG.
